UNITED STATES PATENT OFFICE.

PAUL ROBERT HEYDEL, OF MORSEMORE, NEW JERSEY, ASSIGNOR TO PEERLESS ROLL LEAF CO., INC., A CORPORATION OF NEW YORK.

TRANSFER METALLIC DEPOSIT.

Application filed September 30, 1920. Serial No. 413,807.

To all whom it may concern:

Be it known that I, PAUL ROBERT HEYDEL, a citizen of the Republic of Germany, residing at Morsemere, county of Bergen, State 5 of New Jersey, have invented certain new and useful Improvements in Transfer Metallic Deposits, of which the following is a specification.

This invention relates to transfer metallic 10 deposits, particularly in roll form.

An object of the invention is to produce a transfer deposit of metallic powder of suitable composition and releasable at elevated temperatures as by means of a heated die 15 operated under pressure in a die press, tipping machine or other transfer effecting device. Such transfer metallic deposit is secured to a strip of paper or like inert material serving as the vehicle for the deposit 20 mass and enabling the deposit material to be wound in rolls, for the convenience of shipment and convenience of use in the die press or other transferring machine.

The transfer metallic deposit made in accordance with my invention comprises a 25 mass of metallic powder the particles of which are bound together by means of a binder or supporting ingredient and coacting to determine the temperature of release 30 of the metallic transfer and other suitable ingredients to produce the desired metallic impression. Preferably a coating of sizing is provided on the transfer mass, on the face of the transfer mass applied to the cover 35 of the book, silk, cotton or other fabric or other article to be embellished. The mass of deposit material is usually secured to a strip of paper or like inert vehicle, which inert vehicle is preferably coated initially 40 with a coating of wax, or the like. Such binder or supporting ingredient is chosen to render the mass of deposit material releasable from the strip of paper within a desired range of temperature, usually from 150° to 45 300° F.

Further features and objects of the invention will be more fully understood from the following description and the accompanying drawings, in which—

50 Fig. 1 is a diagrammatic view showing in side elevation suitable apparatus, including a table and a vaporizing device for forming the transfer deposit mass;

Fig. 2 is a diagrammatic view of the table

viewed in the direction transverse to that 55 of Fig. 1, showing also a roll of paper strip supplied to the table and the resulting paper strip coated with the transfer deposit mass;

Fig. 3 is a perspective view of one form 60 of the resulting roll;

Fig. 4 is a diagrammatic view of a die press for transferring the deposit metallic mass to the article to be ornamented;

Figs. 5 and 6 are diagrammatic views of modified apparatus for carrying out my in- 65

vention.

Referring to Figs. 1 and 2, the transfer deposit mass may be produced by the use of a table 1 provided with a suitable hood 2 open at its side 3 and closed at the opposite 70 side 4 and provided with entry and discharge openings at the ends as indicated at 5, 6, respectively. The paper strip 7 is usually fed from a roll on a suitable reel 8, or other carrier, and its unwound end passed through 75 the entry opening 5 onto the face of the table 1. The table 1 is preferably made of glass or similar translucent or transparent material, the purpose of which will appear from the following.

The paper is preferably coated, with an initial layer 10 indicated in Fig. 1, of waxy material, such as bees-wax. Such waxy coating may be applied by running the paper through a bath of the waxy material, the 85 speed of the paper therethrough determining the thickness of the layer of the waxy material.

A mixture of the powdered metal and the supporting and binding ingredient admixed 90 with a suitable volatile solvent or miscuent, is made and placed in the bottle 11 of a suitable spraying device, such as an Eureka polinatic spray, in which type of spray the nozzle 12 is supplied with compressed air 95 from a reservoir 13, or the like. The flow of the spray is controlled manually by means of the spring valve 14. Such spraying device, as is understood by those skilled in the art, embodies suitable means for admitting a 100 portion of the compressed air into the bottle 11 for maintaining the contents of the bottle 11 thoroughly stirred.

The spray is directed into the hood 2 and above and toward the wax coated paper 9 105 until the deposited metallic mass is sufficiently thick.

The thickness of the deposit mass is deter-

mined by the color and the intensity of the transmitted light supplied by one or more lamps 16 placed below the table 10.

After the portion 9 of the paper has been 5 sufficiently coated with the transfer deposit mass, it is drawn through the discharge opening 6 of the hood 2 and hung on suitable racks 17 and left to dry in the atmosphere or led through a drying oven or the 10 like.

Upon volatilization of the volatile ingredient or ingredients the resulting transfer deposit mass comprises an intimate mixture of the metallic powder and the binder or supporting ingredient and controlling the temperature of release to transfer the metallic mass, but at ordinary temperatures binding the particles of the metal powder together as a mass and protecting the desired metallic 15 characteristics from the atmosphere or other deterioration.

Bronze powders, aluminum powders, or mixtures of aluminum and bronze or of other metal powders containing either a single metal or alloy or mixtures of any desired 20 metals may be employed.

The outer face of the transfer deposit mass may be coated or covered with sizing 19, such as egg albumen, varnish or the like, 25 as is indicated in Fig. 3.

Such transfer deposit mass is usually secured to a strip and in such form of my invention, the binder serves to secure the metallic transfer mass as a whole to the paper 30 strip.

Such transfer deposit mass is usually fed as a roll into a tipping machine or die press, such as indicated in Fig. 4, described and claimed in United States Letters Patent No. 40 1,333,168, patented March 9, 1920, Nelson E. Funk, assignor to Peerless Roll Leaf Co., Inc., and entitled Die press.

In Fig. 4, I have indicated at 20 a roll of the metallic deposit material, the unwound 45 end 21 of which is passed about the fixed guide rolls 22, 23, thence below the die 24 and above the movable platen 25, thence over the guide rolls 26, and 27, carried by the platen 25 and ultimately between the take-up 50 roller 28. The platen 25 is mounted on the bed 29 to be reciprocated from its extreme left-hand position as is indicated in Fig. 4, to its extreme right-hand position, as will be more fully understood by reference to the 55 aforesaid Letters Patent.

The article 30, such as a length of silk, or the like, is placed on the platen 25. The die 24 is suitably removably held in the die-holder 31, mounted to be reciprocated vertically under pressure by toggle levers operated by foot or other power, the stage of contact of the die 24 and the metallic strip 21 and the article 30 being effected when the article 30 is at rest, i.e., when the platen 25 is 60 in its position shown in Fig. 4.

The die 24 is heated by any suitable means, such as a gas burner 32, mounted say on the platen 25 as shown, the guard 33 being provided to preclude the flame from scorching or igniting the paper strip. 70

The arrangement shown in Fig. 4, is particularly devised to strip the used deposit strip from the die 24 and to automatically feed the deposit strip for varying extents determined by the size of the die or work 75 to be ornamented.

As a supporting ingredient, I prefer rosin, refined of any objectionable impurities incident to its particular source of manufacture and having a substantially definite temperature of fusion or of becoming practically fluid in the presence of the beeswax or equivalent waxy ingredient. I have discovered that such supporting ingredient is entirely inert toward the particles of metal 80 powder at ordinary temperatures and also protects the tone of color and degree of brilliancy of the metallic powder from deterioration. 85

As a volatile ingredient, I prefer benzine, 90 which in the case of the usual rosins is a solvent, and also a solvent for beeswax.

The metallic mass having the aforesaid features may also be formed by the method and apparatus indicated in Fig. 5. The roll 95 of paper is indicated at 40, its free end being passed under the positioning roller 42 and over the applying roller 44 rotatably mounted in a suitable receptacle for the bath 43 containing a mixture of beeswax and benzine and rosin, whereafter the paper thus coated with a deposit comprising beeswax and rosin with benzine volatilizing therefrom is passed over the drying racks comprising the upper rollers 45 and lower roller 46, and for an extent to permit the beeswax-rosin deposit to become sufficiently "sticky," whereafter the paper is passed about the guide roll 47 and thence over the bronzing roller 48. The feed box of the metal powder is indicated at 49 and provided with any suitable distributor roller; the rollers 50 are usually of discs of felt, for buffering the metal powder applied by the plush or bronzing roller 49. The paper is passed about the guide roller 51 and then wound on the winding roller 52, by any suitable means. 100

In the method shown in Fig. 6, the procedure shown in Fig. 5 is largely repeated, Fig. 6, however, showing the initial application of wax directly to the paper prior to the deposit of the beeswax-rosin deposit. In Fig. 6 I have shown the bath 55 provided with the applying roller 56 and the upper roller 57, between which rollers the paper 115 41 passes.

It will be understood that the thickness or degree of deposit of the beeswax-rosin deposit and of the initial wax deposit is regulated by the speed of travel of the paper 120 130

through the feeding devices of the respective baths, or may be controlled by the particular volatile solvent employed or by the extent of pressure of the squeegeeing roller or 5 equivalent means as will be understood by the art.

Whereas I have described my invention by reference to specific forms thereof, it will be understood that many changes and modifications may be made without departing 10 from the invention, as described by the appended claims.

I claim:

1. A transfer metallic deposit comprising 15 a strip of paper bearing a mixture composed of beeswax, rosin and powdered metal, the

beeswax and rosin being substantially uniformly intermixed and the powdered metal distributed on the beeswax and rosin.

2. A transfer metallic deposit comprising 20 a strip of paper bearing a layer formed of a mixture composed of beeswax, rosin and powdered metal, the beeswax and rosin being intimately intermixed with one another and the powdered metal distributed on the 25 beeswax and rosin and a layer of sizing disposed on the outer face of the aforesaid first-named layer.

In testimony whereof I have signed this specification this 29th day of September, 30 1920.

PAUL ROBERT HEYGEL.
